Inventor:

Charles Edmond Ross

UNITED STATES PATENT OFFICE.

CHARLES EDMOND ROSS, OF LINCOLN, NEBRASKA.

ACETYLENE-GAS MACHINE.

SPECIFICATION forming part of Letters Patent No. 643,982, dated February 20, 1900.

Application filed September 26, 1898. Serial No. 691,957. (No model.)

To all whom it may concern:

Be it known that I, CHARLES EDMOND ROSS, a citizen of the United States, residing at Lincoln, in the State of Nebraska, have invented 5 a new and useful Acetylene-Gas Machine, of which the following is a specification.

My invention relates to improvements in acetylene-gas machines for both portable and stationary lighting in which the heat of water 10 is used to keep a sufficient pressure on the gas and automatically wet carbid to keep the proper volume of gas on hand; and the objects of my improvements are, first, to make a gas-machine that is simple and not likely 15 to get out of order; second, to make a gas-machine without any automatic valves or levers to get out of order, and, third, to make a gas-machine that can be used for portable as well as stationary work. I attain these 20 objects by the mechanism illustrated in the accompanying drawing, in which the figure is a vertical section of the entire machine.

It consists of the following parts: lower tank D and upper tank E, which have connected to them generator A, water-valve B, three-way cock C, escape-pipe J, reducing-valve H, and pipe F, which connects the upper and lower tanks.

The machine will be understood after describing its operation, which is as follows: Shut off the water-valve B and throw the three-way cock so that the generator will be open outdoors through escape-pipe J, loosen thumb-screws K K and take the generator 35 away from the lid, which is held stationary by the pipe connections, place carbid in generator, replace generator and fasten it gas-tight by thumb-screws and gasket, open valve B, and throw the three-way cock to the point 40 that closes the connection from generator to escape-pipe and connects lower tank D with generator A. The lower tank D must be nearly full of water when machine is first started. Then only a little need to be put in 45 by way of the upper tank each time the generator is recharged. As the water in tank D is above the water-pipe B, it will be seen that water will flow through valve and pipe B onto the carbid, and as it does this gas will be generated and flow by way of the three-way cock 50 into the lower tank D, and as the gas accumulates in tank D it forms a pressure and

drives the water up into the upper tank by way of the pipe F until the water in lower tank gets below water-pipe B and stops the flow of water onto the carbid, and therefore 55 stops the generation of gas. If by chance there should happen to get too much water onto the carbid in generator A and more gas would be generated than lower tank D 60 could hold, after it has driven all the water up into the upper tank the surplus gas will also pass up pipe F and up through water in upper tank and escape outdoors through pipe J. As the gas is used from tank D the 65 water will flow from upper tank E back through pipe F into lower tank until it gets high enough to flow into the water-valve B again and start the generation of gas, as before. This operation will be kept up until 70 all the carbid in generator A is exhausted. In this form of gas-machine there will be a variation in the pressure of gas. It is therefore necessary to have a pressure-regulating valve to keep a constant pressure to the burners. The valve for that purpose is shown at 75 H, which is connected to the pipe I, leading to the lights. It will be understood that this valve may be in the form of any of the well-known pressure-regulators used for similar 80 purposes.

This machine can be made in a variety of shapes to fit any place in a house or railroad car where it would be most convenient to have it. The tanks may be made long and stand 85 one above the other in a corner or placed horizontal on brackets.

By the special arrangement of the pipe J with branches leading to both the upper and lower chambers and to the generator and with 90 a single valve controlling its connection with the lower chamber and with the generator I provide a simple easily-operated mechanism by which to effectually control the operation and to permit the ready renewal of the carbid. 95

I am aware that prior to my invention acetylene-gas machines have been made in many different forms; but I have not seen or heard of any like the one set forth in the above specification.

What I claim, and wish to secure by Letters Patent, is—

1. In an acetylene-gas machine, the combination of the upper tank, the lower tank, the

pipe leading from the upper to the lower tank, the generator, the escape-pipe leading upward from the generator and having upper and lower branches connecting it with the lower tank, a valve controlling the escape-pipe at the joint therewith of the upper connection with the lower tank and a valve controlling the lower branch of the escape-pipe, substantially as set forth.

10 2. An acetylene-gas machine comprising the upper and lower tanks, the pipes connecting the upper and lower tanks, the offtake-pipe I, the generator, the escape-pipe leading

from the generator and having a branch connecting it with the upper tank and upper and lower branches connecting it with the lower tank, a valve in the lower branch connection, and a valve controlling the escape-pipe at the juncture therewith of the upper branch connection with the lower tank, substantially as set forth.

CHARLES EDMOND ROSS.
